UNITED STATES PATENT OFFICE.

SAMUEL W. CHILDS, OF CROOKED RUN, VIRGINIA.

BOW-REST FOR CARRIAGE-TOPS.

SPECIFICATION forming part of Letters Patent No. 470,832, dated March 15, 1892.

Application filed October 31, 1891. Serial No. 410,522. (No model.)

To all whom it may concern:

Be it known that I, SAMUEL W. CHILDS, a citizen of the United States, residing at Crooked Run, in the county of Culpeper and State 5 of Virginia, have invented certain new and useful Improvements in Bow-Rests for Carriage-Tops; and I do declare the following to be a full, clear, and exact description of the invention, such as will enable others skilled 10 in the art to which it appertains to make and use the same, reference being had to the accompanying drawings, and to the letters of reference marked thereon, which form a part of this specification.

15 This invention relates to certain new and useful improvements in that class of devices which are commonly known as "top-props" and which are designed to support the carriage-top when the same is lowered and prevent the jarring and rattling and side movements thereof.

20 To this end and to such others as the invention may pertain the same consists in the peculiar construction and in the novel combination, arrangement, and adaptation of parts, all as more fully hereinafter described, shown 25 in the accompanying drawings, and then particularly defined in the appended claim.

The invention is fully illustrated in the 30 accompanying drawings, which, with the letters of reference marked thereon, form a part of this specification, and in which—

35 Figure 1 is a perspective view of my device, the same being shown as detached from the vehicle. Fig. 2 is a side view of a portion of a carriage provided with my invention, shown as in actual use. Fig. 3 is a vertical cross-section showing the same, the parts being shown upon an enlarged scale. Fig. 4 is a 40 modification.

Reference now being had to the details of the drawings by letter, A designates the prop, which consists simply of a strip of spring-steel, which is bent at its longitudinal center 45 to form a loop B, above which the strip is bent inwardly from either side to form the contracted portion C, and from this point the ends of the strip are bent outwardly to form the flaring or outwardly-inclined arms D and

D', between which the carriage-bow is received, as will presently appear.

50 E is an arm, which is secured to the rear face of the seat-back of the carriage and extends laterally therefrom. This arm generally extends for three to six inches in length 55 and serves to receive and support the weight of the carriage-top when the same is lowered.

F is a band or clip-iron, which is adapted to be fitted over the arm E and secured thereto by means of a set-screw F', which is passed 60 through the ends of the clip-iron below the lower face of the arm E. Pending from the lower face of the curved upper portion of the clip E is a lug or pin E', which passes through an opening A' in the prop A and holds the 65 same in position.

In use the prop A is placed upon the clip F, and the said clip is placed upon the arm E and moved along the same until a point in exact alignment with the top bow of the carriage-top is reached and is secured at this 70 point by tightening the set-screw. When the carriage-top is lowered, the top bow will be received between the flaring or inclined arms D and D' of the prop, and the weight of the top 75 will cause the said arms to be forced apart against the tension of the spring material of which the prop is made, thus causing the said bow to pass the contracted portion C, where it will be securely held against lateral play. 80

It is sometimes found that in cases in which side curtains are used upon the carriage that the outer arm D' of the prop is likely to interfere with the curtain, and for use in this case I provide a modified form of prop, such 85 as I have shown in Fig. 4 of the drawings, this modification consisting, essentially, in dispensing with the inner arm D'.

It is deemed important that the parts D and F be arranged at right angles to each other 90 and that they be loosely held together, so that the part D may have sufficient play to prevent raising of the bow.

Having thus described my invention, what I claim to be new, and desire to secure by Letters Patent, is—

As an improved article of manufacture, the herein-described top-prop or support for

buggy-tops, the same consisting of a strip of
spring metal bent at its longitudinal center
to form a loop and having inclined upwardly-
extending arms, as described, the clip F, hav-
ing its loop portion arranged at right angles to
and loosely held in the loop of the said strip,
means for securing the clip to the top, sup-
porting-arms attached to the buggy-seat, and
the lug or pin E', integral with the clip and

engaging an opening in the prop A, substan- 10
tially as described, and for the purpose speci-
fied.

In testimony whereof I affix my signature in
presence of two witnesses.

SAMUEL W. CHILDS.
